Primary Examiner — Cynthia Ramirez*Assistant Examiner* — Michael A Maharajh(74) Attorney, Agent, or Firm — Marshall, Gerstein & Borun LLP(57) CLAIM

The ornamental design for a hand held massager element, as shown and described.

DESCRIPTION

FIG. 1 is a perspective view of a hand held massager element, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a bottom perspective view thereof.

The broken lines in the drawings are for the purpose of illustrating portions of the hand held massager element, which form no part of the claimed design.

1 Claim, 8 Drawing Sheets(56)
